UNITED STATES PATENT OFFICE.

HUBERT HARRY HARSHMAN, OF TORONTO, ONTARIO, CANADA.

DISPLAY CABINET OR CONTAINER FOR STATIONERY OR OTHER MERCHANDISE.

Application filed May 7, 1928. Serial No. 275,890.

My invention relates to improvements in display cabinets or containers for stationery or other merchandise, and the object of the invention is to devise an adjustable retaining means in a container having a downwardly and forwardly inclined top for holding merchandise such as cards against a face of the cover so that when the cover is closed and the cards carried to an inverted position they will be definitely held in place and when the cover is raised to its open or substantially vertical position such retaining means may be adjusted from a position adjacent the top of the card to a position 10 adjacent the bottom of the card to simultaneously release all the cards for free withdrawal of any one card, and yet hold the remaining cards in a display position, or, adjusted to return to a position adjacent 15 the upper end of the card so as to hold the card in place when carried towards an inverted position, and at the same time devise means for preventing the retaining means catching on a ribbon bow, or any superimposed card portion such as in valentines or 20 anything else projecting from the face of a card body, as the retaining means is adjusted from one position to the other, and it consists essentially of the arrangement 25 and construction of parts as hereinafter more particularly explained.

Fig. 1 is a perspective view of my cabinet or container shown in the open position.

Fig. 2 is an enlarged perspective detail 35 showing one of the retainers and the various positions it assumes in dotted lines.

Fig. 3 is a vertical section through a portion of the container cover and showing one of the retainers and the parts coacting there- 40 with.

In the drawing like characters of reference indicate corresponding parts in each figure.

1 indicates the body of the container 45 which is provided with an inclined top 1^x. The container body 1 may be utilized for the containing of stock or for any other purpose desired. 2 is the container cover which is hingedly connected at 2^x to the body 1 at 50 the upper end of the inclined top thereof. 3 are a plurality of channel bars extending transversely of the face of the cover and forming ledges on which the lower edges of the cards 4 rest. 5 and 6 are slide bars held 55 in guideways 7 and 8 at each side of the face of the cover, the bars 5 and 6 being

preferably provided with thumb pieces 5^x and 6^x by which the slide bars may be moved manually longitudinally.

The bar 5 is provided with inturned end 60 portions 9 and 10 and the bar 6 with opposing inturned end portions 11 and 12. Between the end portions 9 and 10 and 11 and 12 extend wires 13 and 14 divided centrally of their length and connected together by a tightening turn buckle 15.

The opposite or upper and lower ends of each wire 13 and 14 is connected to the inturned portions 9 and 10 and 11 and 12 by tension springs 16 thereby keeping the 70 wires 13 and 14 taut. Extending transversely between the wires 13 and 14 and adjacent each ledge 3 is a transverse retaining wire 17.

18 are a series of stationary cam projections which are semi-oval in form and secured to the face of the cover 2 so as to extend edgewise therefrom. A cam projection 18 is located adjacent each transverse 75 retaining wire 17.

When it is desired to close the cover all it is necessary to do is to move the slide bars 13 and 14 longitudinally upward. This movement carries the transverse retaining wires 17 in a corresponding direction and as they are carried upward each wire rides upon the edge of the corresponding cam projection 18, thereby forcing the wire outward from the face of the card so that such wire will pass upward free of the face and as 90 it travels to the upper end of the cam drops gradually onto the face of the card so as to again grip it at its upper end or into the position it should assume for retaining the card in place when carried toward an inverted position by the closing of the cover 2.

When the cover is open and it is desired to display the cards all it is necessary to do is to move the slide bars 13 and 14 in the opposite direction, the retaining wire 17 returning over the edges of the cams 18 so as to drop onto the face of the card adjacent its lower end and leave the cards free to be withdrawn.

It will thus be seen by this movement of the retaining wires that if any projecting portion is carried upon the face of the card the wire as it rides over the edge of the cam in either an upward or downward direction is lifted clear of the card face and thereby avoids any liability of catching any such projection which would have a tendency to

displace the card or make the device awkward to operate.

What I claim as my invention is:

1. In a display cabinet or container for stationery and other merchandise, the combination with the cover thereof of a series of transverse supporting ledges carried on a face of the cover and upon which the lower edges of the stationery or like merchandise are adapted to rest, a retaining wire extending transversely of the cover adjacent each ledge, carrying means for the ends of the retaining wires adjustably carried in the cover to move upward or downward, and means for carrying the retaining wires clear of the face of the card as such wires are carried from the upward to the downward position or vice versa.
2. In a display cabinet or container for stationery and other merchandise, the combination with the cover thereof of a series of transverse supporting ledges carried on a face of the cover and upon which the lower edges of the stationery or like merchandise are adapted to rest, a retaining wire extending transversely of the cover adjacent each ledge, carrying means for the ends of the retaining wires adjustably carried in the cover to move upward or downward, cam projections having an arc-shaped periphery secured to the cover so that such periphery projects therefrom and over which the retaining wires ride as they pass from an upward to a downward position or vice versa.
3. In a display cabinet or container for stationery or other merchandise, the combination with the cover thereof of a series of transverse supporting ledges carried on the face of the cover and upon which the lower edges of cards or other like merchandise are adapted rest, slide bars guided to move longitudinally at each side of the cover and at each end of the ledges and provided with inturned upper and lower ends, carrying wires extending between such

inturned ends, tension springs connecting the ends of the carrying wires to the inturned ends, transverse retaining wires extending between the carrying wires, and means for forcing the retaining wires outward from the face of the cards as they are carried from their upper to their lower position or vice versa.

4. In a display cabinet or container for stationery or other merchandise, the combination with the cover thereof of a series of transverse supporting ledges carried on the face of the cover and upon which the lower edges of cards or other like merchandise are adapted to rest, slide bars guided to move longitudinally at each side of the cover and at each end of the ledges and provided with inturned upper and lower ends, carrying wires extending between such inturned ends, tension springs connecting the ends of the carrying wires to the inturned ends, means interposed in the length of the carrying wires for adjusting the tension thereon, transverse retaining wires extending between the carrying wires, and means for forcing the retaining wires outward from the face of the cards as they are carried from their upper to their lower position or vice versa.

5. In a display device for cards and other stationery or merchandise, a supporting member, a series of transverse card supporting means carried by a face of the supporting member and upon which the lower edges of the aforesaid cards are adapted to rest so as to bear against the face of the supporting member, a retainer extending transversely of the cover, means for moving the retainer from a position adjacent the lower edge of the card to a position adjacent the upper edge of the card or vice versa, and means for carrying the retainer as it is passed from one position to the other clear of the face of the card.

HUBERT HARRY HARSHMAN.
